UNITED STATES PATENT OFFICE.

ELLSWORTH ELY, OF LOCKPORT, NEW YORK.

ANTI-RATTLER FOR THILL-COUPINGS.

SPECIFICATION forming part of Letters Patent No. 225,975, dated March 30, 1880.

Application filed January 27, 1880.

To all whom it may concern:

Be it known that I, ELLSWORTH ELY, a citizen of the United States, residing in Lockport, in the county of Niagara and State of New York, have invented certain new and useful Improvements in Anti-Rattling Devices for Shaft-Shackles, of which the following is a specification.

The object of this invention is to prevent the rattling of shaft or thill couplings; and it consists of a cast metallic shell made concave on one side, so as to present a large wearing-surface to the periphery of the shaft-eye, and provided with a socket on the opposite side to receive the large end of a cone-shaped coiled spring, the outer end of the spring being small or pointed, so as to allow the concave portion of the shell to adjust itself, so that its whole surface shall press evenly against the periphery of the shaft-eye or other similar device to which it may be applied, whether it be exactly in line or not, which would not be the case if the ordinary spiral spring were used, as will be more clearly shown by reference to the drawings, in which—

Figure 1 is an end elevation; Fig. 2, a plan or top view; Fig. 3, a vertical section through the center of the shell in line X X, Fig. 2; and Fig. 4 represents a longitudinal section through a portion of a thill-coupling, showing my invention in position.

A represents the shell, which is of cast metal, and is formed with the concave side B, to fit around the shaft-eye sufficiently to hold it in position and to present a large wearing-surface to the periphery of the shaft-eye between the ears of a shaft-shackle. It is provided on each end with a projection, C, to fit between the ears of the shackle. On the back side of the shell A is a socket, D, to receive

the large end of the coiled spring E, to which it is connected, as shown in Figs. 1 and 2. The small end E' of the spring E, when the device is in place in a thill-coupling, rests against the shackle, so as to allow the concave portion to adjust itself to the periphery of the shaft-eye.

If desired, the small end of the coiled spring may be fitted into a little depression in the shackle; but the form of the shell and its connection therewith is such that it cannot move from its place, and consequently this would be unnecessary.

The spring E is made of a flat thin strip of steel, and is formed so that the width instead of the thickness takes the strain, thereby producing a stronger spring in the same compass than can be made in the ordinary way.

In Fig. 4 I have shown the device in the proper position to prevent the rattling of a shaft or thill. F is the back of the shackle, against which the small end of the spring presses; and G represents the shaft-eye, against the periphery of which the concave portion of the shell is fitted, and presses with sufficient force to prevent rattling.

This device is much more durable than the ordinary leather or rubber spring used for the same purpose; besides, it is stronger and better adapted for the purpose.

70

I claim as my invention—

An anti - rattling device consisting of the shell A, having the concave side B, ends C, and socket D, in combination with the cone-shaped spring E, constructed substantially as 75 specified, for the purposes described.

ELLSWORTH ELY.
